Primary Examiner—Ted Shooman*Assistant Examiner*—Mitchell I. Siegel*Attorney, Agent, or Firm*—Cooley Godward LLP; Craig P. Opperman[57] CLAIM

The ornamental design for a golf club head, as shown.

DESCRIPTION

FIG. 1 is a perspective view of a golf club head, showing our new design;

FIG. 2 is a bottom plan view thereof;

FIG. 3 is a rear elevational view thereof;

FIG. 4 is a front view thereof;

FIG. 5 is a right elevational view thereof; and,

FIG. 6 is a left side elevational view thereof.

The broken line showing of a hosel is for illustrative purposes only and forms no part of the claimed design.
